(57) **ABSTRACT**

Systems and methods for actuating a downhole tool. In some embodiments, the methods include the steps of providing a conductor having a first end positioned at a surface location and a second end positioned at a first downhole location within a wellbore, receiving an electrical signal from the conductor at the first downhole location, transmitting an acoustic signal through the wellbore, starting at the first downhole location and arriving at a second downhole location, receiving the acoustic signal at the second downhole location, moving a spring-forced piston in response to the acoustic signal, and actuating a downhole tool from a first configuration to a second configuration by moving the spring-forced piston with force generator by a spring in combination with an atmospheric chamber.

**FIRE ON DEMAND ATMOSPHERIC
BARRIER VALVE USING WIRELESS
SIGNAL TRANSMISSION**

**CROSS-REFERENCE TO RELATED
APPLICATION**

The present application claims priority to U.S. Provisional Application No. 63/537,121, filed Sep. 7, 2023, the entire disclosure of which is incorporated herein by reference.

BACKGROUND

Wellbores are often drilled through subterranean formations for hydrocarbon exploration and recovery. Well completion involves various downhole procedures prior to allowing production fluids to flow thereby bringing the well online. Valves may be installed downhole to perform a variety of different functions. For example, valves may be installed downhole to form a barrier, isolating a section of the subterranean formation and/or wellbore. In some instances, the downhole valve may be used to isolate one downhole section of the wellbore from another downhole section of the wellbore such that the integrity of a downhole tubular (e.g., casing, liner, etc.) can be tested. In other instances, the downhole valve may be used to isolate a target reservoir from other sections of the wellbore, for example, to isolate the target reservoir while an upper completion is being installed. In yet other instances, the downhole valve may be used to isolate sections of the wellbore for flow control.

Wireline tools have been used for actuation of the down-hole valves. However, multiple wireline intervention trips into the wellbore may be needed to open/close the downhole valve from the wellbore, adding unnecessary expense to wellbore operations. Drawbacks to hydraulic control lines are the need for a control line connection from the surface to the downhole valve, which may be problematic when crossing packers and upper/lower completions. Downhole valves have also been actuated from the surface with a hydraulic control line. Techniques have also been implemented for sending pressure signals from the surface to actuate downhole valves. These techniques typically rely on a pressure signal sent from the surface to transition the downhole valve to a different configuration. Drawbacks to pressure signals are repeated pressure signals (e.g., up to 20 cycles or more) may need to be sent to the downhole valve for actuation, which may take undesirable rig time to accomplish.

BRIEF DESCRIPTION OF THE DRAWINGS

These drawings illustrate certain aspects of some of the embodiments of the present disclosure and should not be used to limit or define the disclosure.

FIG. 1 illustrates a wellbore system including actuation of a downhole tool in accordance with some embodiments of the present disclosure.

FIG. 2 illustrates a sectional view of a downhole tool in accordance with some embodiments of the present disclosure.

FIG. 3 illustrates a sectional view of an actuation system in accordance with some embodiments of the present disclosure.

FIG. 4 illustrates a sectional view of a latch assembly in accordance with some embodiments of the present disclosure.

2

FIG. 5A illustrates a sectional view of a spring assembly in accordance with some embodiments of the present disclosure.

FIG. 5B illustrates a sectional view of the spring assembly shown in FIG. 5A where the latch has been actuated and the piston has travelled horizontally to the right.

FIG. 6 illustrates a sectional view of a ball valve assembly in accordance with some embodiments of the present disclosure.

DETAILED DESCRIPTION

Some embodiments provide a method of actuating a downhole tool, comprising the steps of providing a conductor having a first end positioned at a surface location and a second end positioned at a first downhole location within a wellbore, receiving an electrical signal from the conductor at the first downhole location, transmitting an acoustic signal through the wellbore, starting at the first downhole location and arriving at a second downhole location, receiving the acoustic signal at the second downhole location, moving a spring-forced piston in response to the acoustic signal, and actuating a downhole tool from a first configuration to a second configuration by moving the spring-forced piston with force generator by a spring in combination with an atmospheric chamber.

Some embodiments provide wherein the downhole tool is a downhole valve, the first configuration is a closed valve and the second configuration is an open valve. Some embodiments provide wherein the downhole tool is a down-hole valve, the first configuration is an open valve, and the second configuration is a closed valve. Some embodiments provide wherein the step of transmitting an acoustic signal is performed by transmitting the acoustic signal through a packer.

Some embodiments provide monitoring acoustic signals over time to establish a detected acoustic signal profile. Some embodiments provide comparing the detected acoustic signal profile to a target acoustic signal profile and performing the actuating step only when the detected acoustic signal matches a target acoustic profile. Some embodiments provide wherein the acoustic signal is a sound wave. Some embodiments provide wherein the acoustic signal is an audible soundwave.

Some embodiments provide a system for actuating a downhole tool comprising a tubular string extending from a surface location through a first downhole location to at least a second downhole location, a conductor extending from the surface location to the first downhole location, an acoustic signal transmitter at the first downhole location that is electrically coupled to the conductor, an acoustic signal receiver at a second downhole location that is downhole from the first downhole location, wherein the signal receiver is configured to receive acoustic signals from the acoustic signal transmitter, a decoder at the second downhole location in electrical communication with the signal receiver and programmed to look for a target acoustic profile, an actuator at the second downhole location in electrical communication with the decoder, a spring-forced piston which moves when a target acoustic profile is received, and a downhole tool at the second downhole location coupled to the spring-forced piston. Some embodiments provide wherein the actuator is triggered when the decoder receives an acoustic signal that matches the target acoustic profile. Some embodiments provide an upper completion seal placed between the first downhole location and the second downhole location. Some embodiments provide an atmospheric chamber which

applies force to the piston when a target acoustic profile is received. Some embodiments provide wherein the tool is a valve and said valve can open or close when the target acoustic profile is received at the decoder.

Some embodiments provide a system for actuating a downhole tool comprising a tubular string extending from a surface location through a first downhole location to at least a second downhole location, a conductor extending from the surface location to the first downhole location, an acoustic signal transmitter at the first downhole location that is coupled to the conductor and adapted to transmit an acoustic signal down the tubular string, a signal receiver at a second downhole location that is downhole from the first downhole location, wherein the signal receiver is configured to receive acoustic signals from the acoustic signal transmitter which are transmitted through the conductor, a signal decoder at the second downhole location in signal communication with the signal receiver, an actuator at the second downhole location in signal communication with the signal decoder, a latch connected to the actuator which releases a spring-forced piston when a specific signal is received at the signal decoder, and a downhole tool at the second downhole location coupled to the spring-forced piston.

Some embodiments provide a pin pusher within the actuator that travels towards a barrier member. Some embodiments provide wherein a fracturing of the barrier member establishes fluid communication between a fluid chamber and a relief chamber. Some embodiments provide an upper completion seal placed in between the acoustic signal transmitter and the signal receiver. Some embodiments provide a relief piston in the actuator that moves once there is fluid communication established between the fluid chamber and relief chamber. Some embodiments provide wherein movement of the relief piston releases the latch inside the actuator. Some embodiments provide wherein the downhole tool is a valve and movement of the spring-forced piston causes the valve to open.

Disclosed herein are methods and systems for remotely transitioning a downhole tool **290** between different operational configurations. Example embodiments disclosed herein include methods and systems for actuating downhole tools **290** (e.g., downhole valves, such as a ball valve) with a wired signal transmitted from a surface **120** location to a first downhole location **230** then an acoustic signal transmitted from the first downhole location **230** to a second downhole location **270**. In some embodiments, the acoustic signal may be transmitted through one or more tubulars **200** installed in the wellbore.

In accordance with present embodiments, a system may be provided that remotely transitions a downhole tool **290** between different operational configurations. The system may include a control system **110** at the surface. The control system **110** may send an electrical signal through a tubing encapsulated cable ("TEC") line **150** (or other suitable electrical conductor) from an electrical signal transmitter within the control system **110** (any type) to a first downhole location **230**. The TEC line **150** may include an armor shell, at least one inner insulator disposed in the armor shell, and at least one electrical conductor disposed within the at least one insulator. The armor shell may include a metal tubing (e.g., stainless steel, alloys of stainless steel) for protection of at least one electric conductor. The acoustic signal transmitter **220** may receive a signal from one or more electrical conductors inside the TEC line **150** and convert the signal to an acoustic signal (or pulse, pattern, frequency, amplitude, or some combination of these) that is then transmitted downhole to a second downhole location **270**, sometimes through a sealing element and/or packer(s). The acoustic signal may be any frequency and amplitude of a sound pressure wave that could be either audible or inaudible. A target acoustic profile may be generated and stored so that the acoustic signal can later be received and decoded and compared to said target acoustic profile.

An actuation system **280** located at the second downhole location **270** may include a signal receiver or sensor **300** that listens for some type of acoustic signal sent through the TEC line **150**. The acoustic signal receiver **300** may be powered, for example, by a battery **320**, by the TEC line **150** or other suitable means. The actuation system **280** may be coupled to a downhole tool **290**, which may be a downhole valve. The actuation system **280** receives the acoustic signal, which may essentially be matched with a command to trigger the downhole tool **290** to a different configuration (i.e. to open or close the downhole valve) such that when a specific acoustic signal is received the actuation system **280** may be triggered. In some embodiments, the actuation system **280** triggers a downhole valve to open. In some embodiments, the actuation system **280** triggers a downhole valve to close. For example, the actuation system **280** may release a spring **400** to push down and rotate open the ball mechanism of the downhole valve. In some embodiments, the spring **400** opening may be assisted by an atmospheric boost assembly.

FIG. 1 illustrates a wellbore system 100 from a surface 120 location through a subterranean formation 250. The wellbore system 100 includes a plurality of wellbore tools interconnected to form a tubular string extending through a casing string 170 that is cemented in as wellbore 160. The wellbore system 100 includes a control system 110 at the surface 120. The downhole system further includes an upper completion 180 and a lower completion 190. A TEC line 150 extends from the control system 110 to an acoustic signal transmitter 220 in the upper completion 180 at a first downhole location 230. The lower completion 190 includes an actuation system 280 and a downhole tool 290.

Even though FIG. 1 depicts the well system in a specific well environment, it should be understood by those skilled in the art that the well system may be used in a variety of different well environments. For example, the well system includes a specific completion with upper 180 and lower 190 completions, but it should be understood that the well system may be used in wellbores that are completed in a different manner. By way of further example, even though FIG. 1 depicts a vertical section of a wellbore, it should be understood by those skilled in the art that disclosed embodiments may be used in wellbore having other configurations including slanted wells, deviated wells, horizontal well or wells having lateral branches. Accordingly, it should be understood by those skilled in the art that the use of directional terms such as above, below, upper, lower, upward, downward, left, right and the like are used in relation to the illustrative embodiments as they are depicted in the figures, the upward direction being toward the top of the corresponding figure and the downward direction being toward the bottom of the corresponding figure. While the wellbore 160 is shown as being cased, the well system may be used in wellbores that are uncased or include uncased sections.

The well system 100 includes a control system 110 at the surface 120. The control system 110 may also include a data acquisition system to receive signals from the wellbore 160, such as pressure and temperature signals, among others. The control system 110 may instruct the downhole tool 290 located in the wellbore 160. The control system 110 may also receive and process signals from surface 120 and/or downhole sensors (not shown). Control system 110 may present to an operator desired operational parameters and other information via one or more output devices, such as a display, a computer monitor, speakers, lights, etc., for example, which may be used by the operator to control the wellbore operations.

Control system 110 may include any instrumentality or aggregate of instrumentalities operable to compute, classify, process, transmit, receive, retrieve, originate, switch, store, display, manifest, detect, record, reproduce, handle, or utilize any form of information, intelligence, or data for business, scientific, control, or other purposes. For example, the control system may be a personal computer, a network storage device, or any other suitable device and may vary in size, shape, performance, functionality, and price. The control system may include random access memory (RAM), one or more processing resources such as a central processing unit (CPU) or hardware or software control logic, ROM, and/or other types of nonvolatile memory. Additional components of the control system may include one or more disk drives, one or more network ports for communication with external devices as well as various input and output (I/O) devices, such as a keyboard, a mouse, and a video display. The control system may also include one or more buses operable to transmit communications between the various

hardware components. Control system may also include models and may process data according to programmed instructions and respond to user commands entered through an input device.

- 5 The well system may include an upper 180 and lower 190 completion. The terms 'lower completion' and 'upper completion' are used to describe separate completion stages that are fluidly coupled or in fluid communication with the next completion stage to allow production fluid to flow. 10 While not shown, the well system 100 may also include one or more intermediate completions between the upper and lower completion. In some embodiments, the lower completion 190 refers to the portion of the wellbore that is across the production or injection zone and which comprises perforations in the case of a cemented casing such that production flow can enter the inside of the production tubing such that production fluid can flow towards the surface. Generally, the completion stages may be run-in with valves open (e.g., downhole valve) and then the valves are subsequently 15 closed by mechanical or other means such that the completion stages can be isolated from each other, as desired, for example, for fluid loss control, pressure testing, etc. 20

The tubular string 200 preferably extends through the upper completion 180. In the upper completion 180, the tubular string 200 may include an upper tubular 140, which may include one or more pipes or other conduits. The upper completion 180 may include an upper completion packer 130 that forms a seal between the upper tubular 140 and the casing string 170 (or other outer tubular). The upper completion 180 may also include a upper completion seal 240 (or other seal assembly) that forms a seal between the upper completion 180 and the lower completion 190. As illustrated here, the upper completion seal 240 may form a seal between the upper tubular 140 of the upper completion 180 and a lower tubular 260 of the lower completion 190. While the upper completion seal 240 is shown, example embodiments may be non-sealing without a seal between the upper and lower completions.

35 The upper completion 180 further includes an acoustic signal transmitter 220 at a first downhole location 230. As illustrated, the acoustic signal transmitter 220 may be positioned in the wellbore 160 and coupled to an exterior surface of the upper tubular 140. A TEC line 150 may extend from the surface 120 to the acoustic signal transmitter 220. As 40 illustrated, the TEC line 150 may extend from the control system 110 to the acoustic signal transmitter 220. The control system 110 may send an electrical signal to the acoustic signal transmitter 220 through the TEC line 150. In some embodiments, the TEC line 150 may be attached to the upper tubular 140. In some embodiments, the TEC line 150 may be run on an exterior surface of the upper tubular 140. In other embodiments (not shown), the TEC line 150 may be run on an interior surface of the upper tubular 140.

45 The tubular string 200 may extend from the upper completion 180 to the lower completion 190. In the lower completion 190, the tubular string 200 may include a lower tubular 260, which may include one or more pipes or other conduits. The lower completion 190 may include a lower completion packer 210 that forms a seal between the lower tubular 260 and the casing string 170 (or other outer tubular). As illustrated, the lower tubular string 260 may be located proximate to the intersection of the upper and lower 50 completions.

55 The lower completion 190 may further include an actuation system 280 and a barrier valve. The actuation system 280 and the barrier valve may both be located at a second downhole location 270. The actuation system 280 may be

attached to the lower tubular 260. As illustrated, the actuation system 280 may be positioned in the wellbore and coupled with the lower tubular 260. In some embodiments, the actuation system 280 may be attached to an exterior surface of the lower tubular 260. In some embodiments, the actuation system 280 may be housed in a sidewall of the lower tubular 260. The actuation system 280 may be coupled to the downhole valve. The actuation system 280 may be used to operate the downhole tool 290 which may include a valve. The actuation system 280 receives the signal, which may be a command to open/close the downhole valve and triggers the downhole tool 290 to transition to a different configuration. In some embodiments, a downhole valve may be configured to provide a complete blockage of flow through the tubular string 200, e.g., in the form of a ball valve assembly 430 including a ball valve 435. In some embodiments, the ball valve assembly 430 including a ball valve 435 is configured to provide a restriction through the tubular string 200, e.g., in the form of an adjustable choke. In still other embodiments the ball valve assembly 430 including a ball valve 435 may be configured as a circulation valve arranged to selectively direct fluid between an interior and exterior of the tubular string 200.

FIG. 2 illustrates a sectional view of a downhole tool 290 in accordance with some embodiments of the present disclosure. In this embodiment, the downhole tool 290 includes an actuation system 280 which connects to a latch assembly 375. A spring assembly 395 may be placed in between the latch assembly 375 and a ball valve assembly 430. Also for this embodiment, an atmospheric boost assembly 444 is used and will be described further below.

FIG. 3 illustrates a sectional view of an actuation system 280 in accordance with some embodiments of the present disclosure. Here the acoustic signal receiver 300 may be positioned to receive acoustic signals sent by the acoustic signal transmitter 220. A battery 320 may be electrically connected to both the acoustic signal receiver 300 and a decoder 310 which may be positioned to trigger a pin pusher 330 in response to receiving a certain signal, pattern, or combination of both from the acoustic signal receiver 300.

The actuation system 280 may be operable for transitioning downhole wellbore tools 290 (e.g., downhole valves such as ball valves) between distinct operational configurations. In some embodiments, the actuation system 280 may be generally housed in a sidewall of the tubular string 200 and includes a acoustic signal receiver 300. The acoustic signal receiver 300 may be operable to receive electric signals, convert or decode these signals with a decoder 310. The decoder 310 is operable to decode the acoustic signal into an electronic instruction to thereby determine whether the actuation system 280 should be triggered to transition the downhole tool 290 between operational configurations. Any suitable decoder may be used. In some embodiments, the decoder 310 includes an electronic circuit including various components such as a microprocessor, a digital signal processor, random access memory, read only memory and the like that are programmed or otherwise operable to recognize the predetermined target acoustic profile and to thereby determine whether actuation system should be operated. When the decoder 310 identifies a match between the signal values received and the target signal profile, the decoder 310 may issue a command to an actuation mechanism, such as a pin pusher 330, which triggers the transitioning of the downhole tool 290 (ex, valve) between operational configurations as discussed in greater detail below. The pin pusher 330 may comprise a linear motor, pneumatic piston, or similar mechanism. The decoder 310 may also include

timing devices to delay or control the time period between detection of the target acoustic profile and issuing the command to the pin pusher 330. The acoustic signal receiver 300, the decoder 310, and the pin pusher 330 may all be operably coupled to a battery 320 or another downhole power source (including the TEC line) to receive power therefrom. In some embodiments, the battery 320 may be rechargeable.

The actuation system 280 further includes a piston 420 that is coupled to a force from the spring 400. In the illustrated embodiments, the piston 420 is slidably disposed in a sidewall of the tubular string 200, which may also be the valve body 390. The spring 400 has a spring force in the first direction (shown by arrow "A") that may be applied to the piston 420 thus making the piston 420 spring-forced in some embodiments. An upper end of the piston 420 may include a latch 380. The latch 380 may be positioned between the outer and inner portions of the valve body 390. The latch 380 releasably secures the piston 420 in place by a projection on the outer of the valve body 390. Displacement of the piston 420 in the first direction may be substantially prevented by the latch 380. Upon release of the latch 380, the spring force from spring 400 and the force generated by the pressure differential between the atmospheric pressure and the well fluids 450 hydrostatic pressure from the atmospheric boost assembly 444 causes the piston 420 to move downward in the first direction causing the downhole tool 290 to change configurations, in some embodiments this causes a valve to open. The atmospheric chamber 434 that may be contained within the atmospheric boost assembly 444 reduces in volume as the piston 420 moves in a direction parallel to the axis of the wellbore so as the tool 290 transitions from one position to another position (ex. as a valve opens or closes in some cases) the spring force generated by spring 400 reduces and the atmospheric pressure force will gradually reduce as the mechanism moves in the direction of Arrow A

A barrier member (eg burst disc) 370 is secured between the fluid chamber 350 and an atmospheric chamber 340 which the pin pusher 330 is disposed. In some embodiments, the fluid chamber 350 is filled with a fluid e.g. hydraulic oil. Barrier member 370 initially prevents actuator fluid from escaping from the fluid chamber 350 into the atmospheric chamber 340. Barrier member 370 is illustrated as a disk member and can be formed from a metal but could alternatively be made from a plastic, a composite, a glass, a ceramic, a mixture of these materials, or other material suitable for initially containing actuator fluid in fluid a chamber, but selectively failing in response to the target acoustic profile being identified by the decoder 310, and the command being issued to the pin pusher 330. In the illustrated embodiment, the pin pusher 330 advances a pin in the atmospheric chamber 340 toward the barrier member 370 to thereby fracture the barrier member 370. In other embodiments, failure of the barrier member 370 may be selectively induced by other types of actuation mechanisms configured to induce failure of the barrier member 370 by chemical reactions, combustion, mechanical weakening or other degradation of barrier member 370. Failure of the barrier member 370 creates an opening in the barrier 370 and establishes fluid communication between the fluid chamber 350 and the atmospheric chamber 340. Actuator fluid may thus exit the fluid chamber 350 and enter the atmospheric chamber 340, which allows the fluid piston 360 to be urged toward the fluid chamber 350 in a second direction (shown by arrow B) by the pressure differential between the atmo-

spheric chamber 340 and the well fluids 450 hydrostatic pressure. Movement of the fluid piston 360 releases the latch 380 of the piston 420.

In some embodiments during operation, acoustic signal receiver 300 detects an acoustic signal, for example, from the acoustic signal transmitter 220 (e.g., shown on FIG. 1) and provides acoustic values to the decoder 310 over time. The decoder 310 monitors the acoustic values and determines whether the acoustic values over a particular time interval match the target acoustic profile saved in the decoder 310. If the decoder 310 identifies the acoustic profile in the acoustic values received, and thereby determines that the actuation system 280 should be operated, the decoder 310 issues a command to the pin pusher 330 to advance the pin. For example, the decoder 310 may route electrical power from the battery 320 to the pin pusher 330, immediately or after an appropriate delay, to allow the pin pusher 330 to operate to induce a failure of the barrier 370. Failure of the barrier 370 creates an opening in the barrier and establishes fluid communication between the fluid chamber 350 and the atmospheric chamber 340. Hydraulic fluid may thus exit the fluid chamber 350 and enter the atmospheric chamber 340, which allows the fluid piston 360 to be urged toward the fluid chamber (arrow B) by pressure acting on fluid piston 360 area from the well fluids 450 hydrostatic pressure. Movement of the fluid piston 360 releases the latch 380 causing the piston 420 to be urged in a first direction (arrow A) by spring 400. Pressure from the piston 420 and tubing exert a force causing the tool 290 to operate or in some embodiments for a valve to open.

A well fluid orifice 410 may be positioned in the interior wall separating the well fluid 450 from the fluid chamber 350, to allow the flow of well fluid 450 from the interior of the tool to flow into other areas of the tool. This allows the hydrostatic pressure of the well fluid 450 to be applied to the fluid piston 360 and atmospheric boost assembly 444. Additionally, in some embodiments the well fluid 450 can flow into other areas of the tool including along and around the latch 380, spring 400, and piston 420. This allows additional pressure from the well fluid 450 to be applied to the piston 420 by the atmospheric boost assembly 444.

FIG. 4 illustrates a sectional view of a latch assembly 375 in accordance with some embodiments of the present disclosure. As described further below, the latch 380 may be actuated once the actuation system 280 is triggered.

FIG. 5A illustrates a sectional view of a spring assembly 395 in accordance with some embodiments of the present disclosure. Here, one or more springs 400 may be used to apply a horizontal force to the latch 380. Well fluid 450 may be permitted to fill the cavity holding the spring 400 and along the piston 420. An atmospheric chamber 434 may be sealed from any surrounding fluids and contain only air or any other compressible gas or mixture of gasses. Horizontal movement of the piston 420 causes horizontal movement in the ball valve mechanism 425 which may comprise one or more components to mechanically connect the movement of the piston to the ball valve 435.

FIG. 5B illustrates a sectional view of the spring assembly 395 shown in FIG. 5A where the latch 380 has been actuated and the piston 420 has travelled horizontally to the right. In this situation, the spring 400 may elongate rapidly thereby compressing the compressible fluid (ex. air) within the atmospheric chamber 434. As noted above, the movement of the piston 420 may cause horizontal movement in the ball valve mechanism 425 which may comprise one or more components to mechanically cause the ball valve 435 to

open or close. In some embodiments, the spring 400 may be a helical spring, compression spring, coil spring, or any combination of these.

FIG. 6 illustrates a sectional view of a ball valve assembly 430 in accordance with some embodiments of the present disclosure where said ball valve assembly 430 can be actuated by movement of the latch 380 to engage with a ball valve 435.

For the sake of brevity, only certain ranges are explicitly disclosed herein. However, ranges from any lower limit may be combined with any upper limit to recite a range not explicitly recited, as well as, ranges from any lower limit may be combined with any other lower limit to recite a range not explicitly recited, in the same way, ranges from any upper limit may be combined with any other upper limit to recite a range not explicitly recited. Additionally, whenever a numerical range with a lower limit and an upper limit is disclosed, any number and any included range falling within the range are specifically disclosed. In particular, every range of values (of the form, "from about a to about b," or, equivalently, "from approximately a to b," or, equivalently, "from approximately a-b") disclosed herein is to be understood to set forth every number and range encompassed within the broader range of values even if not explicitly recited. Thus, every point or individual value may serve as its own lower or upper limit combined with any other point or individual value or any other lower or upper limit, to recite a range not explicitly recited.

Therefore, the present embodiments are well adapted to attain the ends and advantages mentioned as well as those that are inherent therein. The particular embodiments disclosed above are illustrative only, as the present embodiments may be modified and practiced in different but equivalent manners apparent to those skilled in the art having the benefit of the teachings herein. Although individual embodiments are discussed, all combinations of each embodiment are contemplated and covered by the disclosure. Furthermore, no limitations are intended to the details of construction or design herein shown, other than as described in the claims below. Also, the terms in the claims have their plain, ordinary meaning unless otherwise explicitly and clearly defined by the patentee. It is therefore evident that the particular illustrative embodiments disclosed above may be altered or modified and all such variations are considered within the scope and spirit of the present disclosure.

What is claimed is:

1. A method of actuating a downhole tool, comprising the steps of:
  - providing a conductor having a first end positioned at a surface location and a second end positioned at a first downhole location within a wellbore;
  - receiving an electrical signal from the conductor at the first downhole location;
  - transmitting an acoustic signal wirelessly through the wellbore, starting at the first downhole location and arriving at a second downhole location;
  - receiving the acoustic signal at the second downhole location; and
  - actuating the downhole tool from a first configuration to a second configuration by fracturing a barrier member between an atmospheric chamber and a fluid chamber in response to the acoustic signal thereby establishing fluid communication between the atmospheric chamber and the fluid chamber thereby moving a spring-forced piston forcing the downhole tool into the second configuration.

11

2. The method of claim 1, wherein the downhole tool is a downhole valve, the first configuration is a closed valve and the second configuration is an open valve.

3. The method of claim 1, wherein the downhole tool is a downhole valve, the first configuration is an open valve, and the second configuration is a closed valve.

4. The method of claim 1, wherein the step of transmitting an acoustic signal is performed by transmitting the acoustic signal through a packer.

5. The method of claim 4, further comprising monitoring acoustic signals over time to establish a detected acoustic signal profile.

6. The method of claim 5, further comprising comparing the detected acoustic signal profile to a target acoustic signal profile and performing the actuating step only when the detected acoustic signal matches a target acoustic profile.

7. The method of claim 6, wherein the acoustic signal is a sound wave.

8. The method of claim 1, wherein the acoustic signal is an audible soundwave.

9. A system for actuating a downhole tool comprising: a tubular string extending from a surface location through a first downhole location to at least a second downhole location;

a conductor extending from the surface location to the first downhole location;

an acoustic signal transmitter at the first downhole location that is electrically coupled to the conductor;

an acoustic signal receiver at a second downhole location that is downhole from the first downhole location,

wherein the signal receiver is configured to receive acoustic signals from the acoustic signal transmitter; a decoder at the second downhole location in electrical communication with the acoustic signal receiver and programmed to look for a target acoustic profile; and an actuation system at the second downhole location in electrical communication with the decoder, wherein the actuation system comprises an atmospheric chamber, a

fluid chamber, a fluid piston, and a barrier member separating the atmospheric chamber from the fluid chamber, wherein the atmospheric chamber comprises the signal receiver, the decoder, and an actuator,

wherein the actuator fractures the barrier member upon a command from the decoder thereby establishing fluid communication between the atmospheric chamber and the fluid chamber which allows the fluid piston to be urged toward the fluid chamber thereby releasing a

spring-forced piston coupled to the downhole tool at the second downhole location.

12

10. The system of claim 9, wherein the actuator is triggered when the decoder receives an acoustic signal that matches the target acoustic profile.

11. The system of claim 10, wherein the downhole tool is a valve and said valve can open or close when the target acoustic profile is received at the decoder.

12. The system of claim 9, further comprising an upper completion seal placed between the first downhole location and the second downhole location.

13. A system for actuating a downhole tool comprising: a tubular string extending from a surface location through a first downhole location to at least a second downhole location;

an electrical conductor extending from the surface location to the first downhole location;

an acoustic signal transmitter at the first downhole location that is coupled to the electrical conductor and adapted to transmit an acoustic signal down the tubular string;

an actuation system at the at least second downhole location comprising an atmospheric chamber, a fluid chamber, a fluid piston, a latch, and a barrier member separating the atmospheric chamber from the fluid chamber, wherein the atmospheric chamber comprises a signal receiver, a signal decoder, and an actuator, wherein the signal receiver is configured to receive acoustic signals wirelessly from the acoustic signal transmitter;

wherein the signal decoder is in signal communication with the signal receiver;

wherein the actuator fractures the barrier member upon a command from the signal decoder thereby establishing fluid communication between the atmospheric chamber and the fluid chamber which allows the fluid piston to be urged toward the fluid chamber thereby releasing the latch, wherein the latch releases a spring-forced piston; and

wherein the spring-forced piston causes the downhole tool at the second downhole location to operate.

14. The system of claim 13, wherein the actuator comprises a pin pusher that travels towards the barrier member.

15. The system of claim 13 further comprising: an upper completion seal placed in between the acoustic signal transmitter and the signal receiver.

16. The system of claim 13 wherein: the downhole tool is a valve and movement of the spring-forced piston causes the valve to open.
